PAIR OF SCISSORS

Salvatore J. Megna, Sacramento, Calif., assignor to
Professional Instruments, Inc., Cincinnati, Ohio

Original design application Nov. 19, 1973, Ser. No.
417,041. Divided and this application Feb. 10, 1975,
Ser. No. 548,772

Term of patent 14 years

Int. Cl. D8—03

U.S. Cl. D8—57

FIG. 1 is an elevational view of a pair of scissors showing my new design;

FIG. 2 is an end elevational view taken from the blade end of the scissors;

FIG. 3 is an end elevational view taken from the handle end of the scissors;

FIG. 4 is a top plan view taken from the upper side in FIG. 1;

FIG. 5 is a bottom plan view taken from the lower side in FIG. 1; and

FIG. 6 is an elevational view showing the side opposite to that shown in FIG. 1.

This is a division of application Ser. No. 417,041, filed Nov. 19, 1973.

I claim:

The ornamental design for a pair of scissors, substantially as shown and described.
